REUSEABLE MULTISTAGE AEROSPACE VEHICLE

James E. Webb, Administrator of the National Aeronautics and Space Administration, with respect to an invention of Harold S. Becker, Palos Verdes Estates, Selwyn Enzer, Orange, William H. Hand, Redondo Beach, Peter Rosati, Garden Grove, and Norman C. Surtees, San Pedro, Calif.

Filed Feb. 5, 1965, Ser. No. 83,866

Term of patent 14 years

Int. Cl. D12—07

U.S. Cl. D71—1

FIG. 1

FIG. 1 is a top perspective view of the reusable multistage aerospace vehicle illustrating the ornamental design of the complete vehicle consisting of a turboramjet propelled carrier vehicle having a spacecraft nested on the top surface thereof;

FIG. 2 is a top plan view thereof;

FIG. 3 is a side elevation of the multistage aerospace vehicle;

FIG. 4 is a front elevation thereof; and

FIG. 5 is a rear view thereof.

What is claimed is:

The ornamental design for a reusable multistage aerospace vehicle, substantially as shown.
